US00D847309S

(12) **United States Design Patent** (10) **Patent No.:** **US D847,309 S**
(45) **Date of Patent:** **** Apr. 30, 2019**

(54) **PIPE ADAPTER FOR WATER HEATER**

(71) Applicants: **NORITZ CORPORATION**, Hyogo (JP); **Living Engineering Co., Ltd.**, Tokyo (JP); **Mirai Industry Co., Ltd.**, Gifu (JP)

(72) Inventors: **Masaki Sugatani**, Akashi (JP); **Takanori Nagano**, Kakogawa (JP); **Hironao Matsunaga**, Amagasaki (JP); **Takahide Hasegawa**, Kakogawa (JP); **Kiyomi Kanamoto**, Tokyo (JP); **Yasuhide Satoh**, Tokyo (JP); **Shohei Matsuda**, Ogaki (JP)

(73) Assignees: **NORITZ CORPORATION**, Hyogo (JP); **Tokyo Gas Living Engineering Co., Ltd.**, Tokyo (JP); **Mirai Industry Co., Ltd.**, Gifu (JP)

(**) Term: **15 Years**

(21) Appl. No.: **29/635,758**

(22) Filed: **Feb. 2, 2018**

(57) **CLAIM**

The ornamental design for a pipe adapter for water heater, as shown and described.

DESCRIPTION

FIG. 1 is a perspective view of a pipe adapter for water heater showing the present design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a cross sectional view taken along line 8-8 of FIG. 7 thereof; and,

FIG. 9 is a front view shown in a state of use.

The evenly spaced broken lines shown in FIGS. 8 and 9 depict environmental subject matter that form no part of the claim.

1 Claim, 5 Drawing Sheets
